UNITED STATES PATENT OFFICE.

MARTHA HALOWELL CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A SIFTER-TOP CAN OR SIMILAR RECEPTACLE.

58,020.

Specification for Design.

Patented May 31, 1921.

Application filed April 8, 1921. Serial No. 459,561. Term of patent 14 years.

To all whom it may concern:

Be it known that I, MARTHA HALOWELL CONNOR, a citizen of the United States, residing in the city of Baltimore, State of Maryland, have invented a new, original, and ornamental Design for a Sifter-Top Can or Similar Receptacle, of which the following is a specification, reference being had to the accompanying drawing, forming a part thereof, wherein—

Figure 1 is a side elevation,

Fig. 2 is a top plan view,

Fig. 3 is a section on line 3—3 of Fig. 1, looking downward, and

Fig. 4 is a section on line 4—4 of Fig. 1, looking in the same direction.

The design is different from that shown in my Design Patent No. 55,749 issued July 13, 1920, in that the can shown herein is narrower at the base from side to side, and deeper from front to back, producing a more chunky appearance at the base and more nearly vertical sides. Furthermore, the flat facets extending down each side are continued substantially to the bottom of the can.

I claim:

The ornamental design for a sifter top can or similar receptacle, as shown.

MARTHA HALOWELL CONNOR.
